HEADLIGHT

Filed Jan. 9, 1925

Inventor:
Winfield R. Du Breuil,
C. B. Bradford, Atty.

UNITED STATES PATENT OFFICE.

WINFIELD R. DU BREUIL, OF ELMHURST, ILLINOIS.

HEADLIGHT.

Application filed January 9, 1925. Serial No. 1,474.

My said invention relates to an improvement in headlights preferably for use on automobiles and other vehicles.

Heretofore automobile headlights have been so constructed that it has been necessary to provide some means of diffusing and breaking up the rays of light in an attempt to prevent the impairment of the sight of the driver of an approaching vehicle, however, the diffused light is still blinding and obviously the provision of such diffusing means prevented the proper projection of the light to most efficiently illuminate the roadway.

It is an object of my invention to provide a headlight having an electric light bulb with a shield or hood therein, positioned directly above the filament and having rear end and side portions extending downwardly around the same slightly below the horizontal plane of the lighting filament, said rear portion being curved and serving as a reflector to project the light forwardly. The forwardly extending portion of said shield prevents the projected light from extending above a horizontal plane but permits the light to project substantially in such plane or very slightly below the same.

Another object of the invention is to provide a light which will more efficiently light the roadway by highly concentrating the light and projecting the same in a narrow shaft or beam instead of diffusing and absorbing the said light.

A further object of the invention is to provide a light of reduced size having a reflecting surface of a short vertical height and a relatively short shield or shade extending therefrom above the light thus eliminating a relatively long shade or shield for the light and obviating the necessity of the conventional reflector.

A still further object of the invention is to provide supporting means for the light which will permit a plurality of adjustments.

A yet further object of the invention is to provide a device of the character described which consists of few parts and is simple and inexpensive to manufacture.

Referring to the accompanying drawings, which are made a part hereof and on which similar reference characters indicate similar parts;

Figure 1 is a longitudinal vertical section of my invention,

Figure 2 is a transverse vertical section of the electric light bulb,

Figure 3 is a longitudinal vertical section of the electric light bulb,

Figure 4 is a section on the line 4-4 of Figure 3,

Figure 5 is a longitudinal horizontal section of the electric light bulb, and

Figure 6 is a section on the line 6-6 of Figure 3.

Figures 7 and 8 are detail views illustrating the different effects of light filaments disposed at varying distances from the reflecting surfaces.

In the drawings, the invention comprises an electric light bulb 10 supported in a socket 11 of a casing 12 mounted by means of a ball and socket or other adjustable means on a supporting bracket 13 attached to the automobile. A lens or cover 14 for the bulb is provided having an external annular flange 15 at its rear end adapted to be engaged by an annular (or plurality of segmental) clamping element 16 secured in any desired manner to the casing 12. The cover or casing 14 is preferably constructed of glass and may have its upper half frosted or otherwise rendered translucent. The socket 11 in the casing 12 is preferably of the usual construction and a signal light 17 also of the usual construction may be suspended in the upper section of the casing adjacent the top thereof.

The electric light bulb constituting the essential feature of my invention comprises a tubular glass casing of a conventional type supported upon a base also of the usual construction. The bulb is constructed with a filament 18 extending substantially diametrically and transversely through the same and is provided with a hood or shade 19 formed by stamping or otherwise from a single sheet of material having diverging bends defining a top flaring toward its forward end and having spaced diverging sides tapering toward the forward end of the headlight said sides preferably being curved and integrally formed with the depending curved rear portion forming a reflector for the filament. The shade 19 is secured to the base of the bulb in any desired manner

and is supported adjacent its front flared portion by means of a pair of spring clamps 20 preferably arcuate in shape and secured at the opposite sides of the shade. Obviously the method of supporting the shade adjacent its front end may be varied and the spring clamps may be dispensed with and the shield supported between spaced indentations in the glass tube.

10 It has been found impractical to provide a bulb of a sufficiently small size to be placed close enough to the reflector as the casing for the filament will readily melt, so that the light from the filament of the bulbs in 15 present use is thrown downwardly directly upon the ground or is projected upwardly beyond a substantially horizontal plane. I have found that by providing the shield for the light inside the bulb and curving said 20 shield rearwardly and closely around the filament that it is unnecessary to have a reflector behind the light other than that formed by the shield and that it is also unnecessary to provide a shield of very great 25 length since the shield and the light are in substantially the same plane and a long shield is unnecessary. To permit the escape of heat around the filament I preferably provide a vent formed by cutting away or 30 striking up a portion of the shield directly above the filament. In the case of the struck-up portion the same will serve as a reflector to illumine the upper portion of the bulb. It will be observed that the lower 35 rim of the shield defines a substantially horizontal plane and that the filament of the light is slightly above said plane.

An essential feature of my invention is 40 that the source of light shall be so related to the reflecting surface above and in front of it as to throw the light in a flat beam close to said surface whereby the bulk of the light will be thrown forward and will 45 strike the ground at a considerable distance from the source of light. For this purpose the actual filament in an electric light should be close to said surface and this way be taken care of by a flat or linear filament 50 with a reflecting surface inside the bulb, as in Figures 1 to 6 of the drawings. This function may also be attained in other ways as by arranging one or more small bulbs with or without small reflectors underneath 55 a reflecting surface which is approximately horizontal, or in place of bulbs other means such as are known to those skilled in the art may be used, e. g., prisms to throw a flat beam of light against a reflecting surface such as is shown in the drawings. It 60 will be understood that in all these arrangements the source of light is to be hidden from any eye above the level of said source, and that the flat narrow source renders it 65 easy to conceal without either locating the reflecting surface at so steep an angle as to

throw all the light on the ground too close to the vehicle for safety, or, what is equally objectionable, making the hood so long as to be awkward and objectionable.

It is desirable to arrange the reflecting surface at the rear so as to throw the rays of light forward parallel to the upper reflecting surface as will be understood by those skilled in the art, so that such rays will extend far forward instead of being 75 reflected down to the ground close to the vehicle.

Figures 7 and 8 illustrate the advantage had by placing the filament or other source of light close to the reflecting surface. 80 When such source, whether it is a linear filament in a horizontal plane, a coiled or bent wire filament lying in a horizontal plane, or a small bulb or other equivalent source, is arranged as illustrated in Figure 85 7, close to a nearly horizontal reflecting surface, the bulk of the light is thrown forward to a considerable distance, whereas when the source is located relatively far from the upper reflecting surface as in Figure 8, the upper reflecting surface (or a hood or casing therefor) must extend down over it to prevent it from rising above a horizontal plane, and therefore the reflecting surface must be at a relatively steep angle 90 as in Figure 8 or else the hood must extend far forward. In the first case the light is thrown down too near to the vehicle for safety and in the second case the hood has an awkward appearance and is more or less 100 in the way.

It will be obvious to those skilled in the art that changes may be made in my device without departing from the spirit of the invention and therefore I do not limit myself to the precise construction shown in the drawings and described in the specification but only as indicated in the appended claims.

What I claim is:

1. In a headlight for automobiles a source of light having means associated therewith for causing a flat beam or shaft of concentrated light relatively wide from side to side and narrow from top to bottom to be projected, and a reflecting surface arranged at a slight angle to the line of said beam to project the bulk of the light forward at a relatively slight angle to a horizontal plane, substantially as set forth.

2. The combination in an incandescent lamp of a transversely disposed filament, and a reflecting shield for said filament comprising an elongated body adapted to be mounted longitudinally of the lamp with the rear extremity of said body curved downwardly around and closely adjacent said filament whereby the light will be projected forwardly and in a substantially flat horizontal plane, substantially as set forth.

3. The combination in an incandescent lamp of a transversely disposed filament, a reflecting shield for said filament comprising an elongated body adapted to be mounted longitudinally of the lamp with the rear extremity of said body curved downwardly around and closely adjacent said filament whereby the light will be projected forwardly and in a substantially flat horizontal plane, and means for supporting the forward portion of said shield, substantially as set forth.

4. The combination in an incandescent lamp of a transversely disposed filament, a reflecting shield for said filament comprising an elongated body adapted to be mounted longitudinally of the lamp with the rear extremity of said body curved downwardly around and closely adjacent said filament whereby the light will be projected forwardly and in a substantially flat horizontal plane the side of said shield being curved downwardly and terminating in a substantially horizontal plane, substantially as set forth.

5. The combination in an incandescent lamp of a transversely disposed filament, a reflecting shield for said filament comprising an elongated body adapted to be mounted longitudinally of the lamp with the rear extremity of said body curved downwardly around and closely adjacent said filament whereby the light will be projected forwardly and in a substantially flat horizontal plane said shield tapering from

its forward portion horizontally to its narrower portion adjacent the filament, substantially as set forth.

6. The combination in an incandescent lamp of a transversely disposed filament, a reflecting shield for said filament comprising an elongated body adapted to be mounted longitudinally of the lamp with the rear extremity of said body curved downwardly around and closely adjacent said filament whereby the light will be projected forwardly and in a substantially flat horizontal plane, a tube-like casing for said shield and filament, and resilient means engaging the edges of the shield and casing adjacent the forward portions thereof for supporting the shield in position, substantially as set forth.

7. The combination in an incandescent lamp of a transversely disposed filament, a reflecting shield for said filament comprising an elongated body adapted to be mounted longitudinally of the lamp with the rear extremity of said body curved downwardly around and closely adjacent said filament whereby the light will be projected forwardly and in a substantially flat horizontal plane said shield being provided with a ventilating passage therethrough adjacent the filament, substantially as set forth.

In witness whereof, I have hereunto set my hand at Washington, District of Columbia, this 8th day of January, A. D. nineteen hundred and twenty-five.

WINFIELD R. DU BREUIL.
